UNITED STATES PATENT OFFICE

HENRY EDMUNDS, OF LONDON, ENGLAND.

SYSTEM OF UTILIZING SECONDARY BATTERIES.

SPECIFICATION forming part of Letters Patent No. 390,464, dated October 2, 1888.

Original application filed June 21, 1885, Serial No. 277,712. Divided and this application filed July 16, 1888. Serial No. 280,019.
(No model.) Patented in England June 15, 1887, No. 8,641.

To all whom it may concern:

Be it known that I, HENRY EDMUNDS, of London, England, have invented a new and useful Improvement in Systems for Utilizing Secondary Batteries, (for which I have obtained Letters Patent in Great Britain, No. 8,641, dated June 15, 1887,) which improvement is fully set forth in the following specification.

This invention has reference more particularly to the utilization of secondary or storage batteries for electric lighting and similar purposes; in installations which include a charging dynamo or dynamos at a central station and groups of batteries at sub stations or localities where their energy is to be utilized; a charging main; local or utilization circuits at each sub-station; and means whereby the batteries may be transferred from the main to the local circuit, and vice versa, for charging and discharging.

Heretofore and prior to my invention it has been common to provide at each station or point of use two sets of batteries, one of which may be receiving its charge in the main while the other is supplying the utilization-circuit, automatic switch mechanism being employed to transfer the sets of batteries from one circuit to the other. The object of such system is to maintain the supply of the utilization-circuit constant, there being always one set of batteries in condition to supply the required energy. It will be observed that the use of such system requires at each station twice the number of batteries actually needed to supply the lamps or other translating devices. The power of the charging-dynamo must be sufficient to charge at once half of all the batteries used—in other words, to supply at all times an amount of energy somewhat in excess of the maximum energy used in the entire system. Excessive leakage and danger to life are necessary incidents of such system. Each set or group of batteries remains in the local circuit until practically exhausted, the potential of the circuit being greatest when a freshly-charged group of batteries is switched in, and thereafter steadily falling as they discharge. This fluctuation causes inconveniences to the consumers, and the strain produced thereby upon the lamps militates against their longevity. It is obvious that as the mini-

55
mum potential of the circuits must be sufficient to maintain the light (if it be a lighting system) the maximum potential will be greatly in excess. A waste of energy is therefore involved.

By the present invention the losses, dangers, and inconveniences above referred to are prevented, and other important practical advantages are secured, as hereinafter set forth. 60 According to my invention the batteries at each station or point of utilization are divided into three or more sets or groups, containing each the same number of cells. I find it convenient to use four groups at each station, and 65 shall describe, for the sake of example, a system employing that number, though it is obvious that the invention is not limited thereto. These groups or sets are one by one, for short and equal periods of time, switched into the 70 charging-main, so that there will always be one set in the charging-main, while three-fourths of all the batteries employed will be supplying the local or working circuit. The system therefore calls for only two-thirds the 75 number of batteries that would be required in the system above referred to; and as the batteries are perhaps the most costly part of such an installation this saving is of great importance. 80 Proportionally less power and smaller generating plant are also required, since only one-fourth, instead of half, the total number of batteries is in the main or charging circuit. Besides the economy thus caused there results the important advantage of smaller leakage, 85 due to the lower pressure employed and less danger to life. The batteries, moreover, are not charged to their maximum capacity and then completely discharged, but are maintained in nearly a uniform condition. For example, there being four sets of batteries, and the period of inclusion of each set in the charging-circuit being fixed at two minutes, each battery will be withdrawn from the working-circuit once in every eight minutes for a fresh 90 charge. This is found to increase greatly the efficiency of the batteries and to retard deterioration. It also produces an important effect in the working-circuit, the pressure in which is, by means of this invention, kept 95 practically uniform, whereby the longevity of the lamps is greatly increased. There being 100

no fluctuation, such as above referred to, in estimating the number of cells necessary to do the work of any particular station this consideration may be disregarded, and no margin of 5 waste energy need be allowed to prevent the minimum potential falling below the limit required, as necessary heretofore.

If the batteries at the several stations are charged in series, it may be desirable to utilize 10 the main or charging circuit for other work in addition to the charge of the batteries. The invention permits this to be done, since the charging circuit is not interrupted nor the potential materially affected by the operations 15 performed in carrying out this invention.

It is essential to the best working of such a system and to the attainment of all the advantages above pointed out that the changes of 20 each set of batteries from the working to the charging circuit should be effected in such manner that, first, no portion of the battery is in connection with both circuits at the same time; second, the charging circuit is never broken; and, third, the discharging-circuit is 25 never interrupted nor its pressure varied, nor any portion of the batteries short-circuited even momentarily. To attain these objects I may arrange resistances (such as wire electrolytic cells or motors or reverse flow of current) to be put into the main circuit during 30 the change of connections. I may effect the changes of circuit necessary in the operation of my system by means of a contact-maker moved at short intervals of time.

35 In order to preserve the continuity of the charging-circuit during the period which elapses between the disconnection of any one section and before the next section is included, the main is closed through a resistance or bypass 40 which has been previously connected in multiple with the section about to be removed but which resistance is in turn removed after the next section of battery has been put in multiple with it in the said main or charging circuit. Similarly in the battery itself the section just charged is put in multiple with the section next about to be charged prior to the latter being removed from the battery and being replaced in the charging-main, uniform- 45 ity of pressure in the local battery being thus maintained and sudden fluctuation of its electro-motive force being prevented.

As the four sections of any group are each included in the charging-main for equal periods, (but only one of the sections at any time being in the main, the other three being included in the local circuit,) it may be assumed 55 that in a period of, say, twenty-four hours, each section or fourth part receives the equivalent 60 of six hours' charge, which enables a full discharge in the local circuit to be maintained for eight hours of that time by the three sections (three fourths of a group) which are at any instant in the local. In the same way in 65 the local circuit for any period of discharge, say eight hours, any one section is discharging for only three-fourths of the eight hours,

(six hours,) since it is periodically removed from the local circuit and put into the charging-circuit for one-fourth of the eight hours, 70 (two hours.)

Having now explained the principle of my invention, I will proceed to describe in detail the apparatus by which it is preferred to carry the same into effect, said apparatus being illustrated in the accompanying drawings.

Figures 1, 2, 3, 4, 5, and 6 are diagrams illustrating the nature and order of the operations performed in transferring the section of such a battery from the local to the main, and vice versa, in the manner above described. Fig. 7 is a front view of the apparatus; Fig. 8, a view of one side, and Fig. 9 a view of the other side. Figs. 10 to 15 are diagrams illustrating the various positions of the moving parts during the cycle of operations, and Fig. 16 a detail showing the meter.

A, B, C, and D represent sections of a battery, each section consisting of any convenient number of cells. In Fig. 1 section A is shown included in the charging-circuit H^a, and sections B, C, and D included in the local or discharge circuit H^b. Before disconnecting the section A from the charging-circuit a resistance, Y, is put in parallel with it, as indicated in Fig. 2, the sections B, C, and D remaining in the local circuit, as before. The section A is now cut out of the charging-main, as indicated in Fig. 3, all the other conditions remaining as before. Section A is then inserted in the battery in parallel with section B, which is next in turn for charging, as indicated in Fig. 4, the other conditions remaining as before. Section B is then taken out of the battery and left isolated, as indicated in Fig. 5, the other conditions remaining as before. Section B is then put in parallel with the resistance Y in the charging-main, as indicated in Fig. 6, the other conditions remaining as before. The said resistance is then removed and the section B receives its charge, and a similar cycle to that already described with regard to section A is thus commenced. This process goes on and each of the sections continues to receive in turn its increment of 100 charge. These changes are effected by any suitable mechanism for changing the circuits, as described, (applied to each group of storage batteries.) For example, such mechanism 105 may consist of a rotating cylinder or drum on the periphery of which are contact-makers arranged to make connection between the charging-main and the sections of the group of secondary batteries and the resistance in the order described; or I may use an arrangement of commutator such as is illustrated in Figs. 7 to 15 wherein cams driven by a suitable-timed motor and mechanism operate rocking levers to insert contact-makers between contact-terminals belonging to each section of battery and to the main and local circuits in the order necessary 110 for effecting the connection and disconnection of batteries as described with reference to Figs. 1 to 6. I will now proceed to describe

115 120 125 130

this arrangement with the aid of Figs. 7 to 15. As shown in the said figures, the positive and negative terminals of each battery are each connected to a separate contact-strip, which 5 is fixed to the base-plate of the machine. On each contact-strip are four spring-contacts, each arranged to make contact with contact-pieces on four vibrating levers, A' B' C' D'. The contact-strips and spring-contacts of the 10 set of batteries *a* are marked *a*⁺ and *a*⁻, respectively, Figs. 10 to 15, the strips and spring-contacts of batteries *b* are marked *b*⁺ and *b*⁻, and so on. The four vibrating levers each carry branches from both the positive and 15 negative of the main and the positive and negative of the local, they being led to contact-strips secured to the backs of the levers. The said levers are operated by cams carried by shaft 17, one of which is shown at D², Fig. 20. The order of vibration of the levers to produce the changes illustrated by Figs. 1 to 6 is illustrated diagrammatically by the companion Figs. 10 to 15. In these diagrams, for the sake of greater clearness and simplicity, but 25 two spring-contacts of each of the contact-strips *a*⁺ *a*⁻ *b*⁺ *b*⁻, &c., are shown. The contact-strips of lever A' are marked *a*² *a*³ *a*⁴, &c., and those of lever B' are marked *b*² *b*³ *b*⁴, &c. Suppose the batteries *a* are in the charging- 30 main, as in Fig. 1, then lever A' will be in the position shown in Fig. 10, its contact-strips touching the spring-contacts of all the batteries. The other levers, B', C', and D', are at this time lifted clear of the corresponding 35 spring-contacts. The branches M⁺ and M⁻ from the main are fastened to strips *a*⁵ *a*⁶, respectively, on lever A', and batteries *a* are thus included in the charging-circuit. The branches L⁺ L⁻ from the local are attached to 40 strips *a*⁵ *a*², respectively, so that the circuit of the local is through the batteries *b* *c* *d* by wire L⁺, strip *a*⁵, spring-contact and strip *b*⁺, battery *b*, spring contact *b*⁻, strip *a*², contact *c*⁺, battery *c*, and so on to branch L⁻, as clearly 45 shown in Fig. 10. It is now desired to put a resistance in parallel in the main with the section A, as in Fig. 2. To effect this I employ a rocking lever and mercury-cups, as shown at S. (The mechanism by which the said rocking lever is operated is hereinafter described.) 50 This rocking lever is caused to assume a horizontal position, as shown in Fig. 11, thus closing the circuit through the mercury-cups *y*, in which the resistance is included, which resistance is thus placed in parallel with section A. Now it is desired to cut the section A out of the main, the resistance alone remaining 55 therein, as in Fig. 3. This is effected by causing the dipping lever S to assume the position shown in Fig. 12, so that the circuit through *y*, in which the resistance is included, remains closed, while the circuit from the main through the section A is broken at *z z*. The section B is next in turn for charging, and the lever 60 B' will next be operated to put the section A in parallel with B in the local circuit, as in Fig. 4, and in Fig. 13 it will be seen that lever

B' has been caused to make contact with its spring-contacts, and the lever A' also maintains its position.

On lever B' the local wires L⁺ and L⁻ are attached, respectively, to contact-strips B⁸ and B⁹, while strips b⁴ b⁵ are connected by a short bridge-wire, b⁶, which thus serves to connect the positive terminals of battery *c* with the negative of battery *a*, the positive of the battery being to the local via spring *a*⁺, strip *b*⁸, wire L⁺; but the positive of battery *c* is also connected with the negative of battery *b* through strip *a*⁴ on lever A', the positive of the latter being connected to local through b⁺ a⁵ L⁺. Thus batteries *a* and *b* are in parallel in the local circuit, as in Fig. 4. On lever B' the branches M⁺ M⁻ of the main are attached, respectively, to strips b⁶ b⁹, but the branch of the main being broken at *z z* only the resistance Y remains therein.

In Fig. 5 the section B is isolated. This is effected, as in Fig. 14, by withdrawing the lever A', which leaves the section A in the local 90 circuit. The connection between the sections A and C is made by the bridge-wire b⁹ on B', which has before been alluded to. The dipping lever S remains as in Fig. 12.

Fig. 6 shows the section B put in parallel 95 with the resistance in the charging-main, and this result is arrived at by the dipping lever S assuming a horizontal position (see Fig. 15) when the main current flows to the batteries by way of *z z*, and also through the resistance Y by way of the mercury-cups *y*. The next operation consists in withdrawing the resistance from the main. This is effected by causing the dipping lever to assume the position shown in Fig. 10. The section B will then receive its charge and commence a similar cycle 100 to that undergone by the section A, being also operated by the dipping lever S and by the levers B' and C' in a similar manner to that in which the levers A' and B' are operated with 105 regard to section A, and from the preceding description the similar operations of charging the sections C and D will be readily understood.

In Figs. 7 and 8 the construction and arrangement of the several contact-strips *a*⁺ *a*⁻, &c., and the vibrating levers, and the course of the several circuits are clearly shown. The branches M⁺ M⁻ of the main are led, respectively, to contact-plates G and H, while the 115 branches L⁺ L⁻ of the local are led, respectively, to the contact-plates I and K. Each of these contact-plates is connected by a separate wire with each of the levers A' B' C' D', so that each lever carries a branch of both the 120 main line and the local. The wire leading from the several plates G H I K to the several levers A' B' C' D' are marked g' g² g³ g⁴ h' h² h³ h⁴, and so on. The circuits of the main are 125 represented by full lines; those of the local by broken lines.

With this particular disposition of regulator-contacts, in order to insure that each section of the group of batteries shall receive

equal charges it is evidently necessary that after having charged sections A, B, C, and D for equal periods of time instead of going back immediately to C from D and charging it and 5 A in the order named, and so on, whereby the groups D and A would only receive half of the charge of their fellows, I cause D (or A) to remain for another period in connection with the charging circuit, and thereby receive 10 an equal charge. Thus it will be seen that the sections are connected with the charging circuit in consecutive equal periods of time in the order indicated by the arrangement of letters following: A B C D, D C B A, A B C D, 15 D C B A, and the battery which receives the last charge of one series of charges receives also the first charge of the following series, and therefore receives a charge during a period of double the ordinary duration; hence in 20 a period of twenty-four hours each battery receives equal increments of charge.

It now remains to describe the mechanism for driving the cams A² B² C² D² which actuate the levers, and the timing apparatus which insures that the cams shall be operated at certain regular intervals electrically.

A shaft, 17, is carried in bearings 18. Upon this shaft is secured a ratchet-wheel, 19. (See Fig. 9.) A pawl, 20, is connected by the link 25 30 35 40 45 50 55 60 65 70 75 80 85 90 95 100 105 110 115 120 125 130 135 140 145 150 155 160 165 170 175 180 185 190 195 200 205 210 215 220 225 230 235 240 main to the working circuit and back again—
goes on continuously. In other words, the
shaft 17 keeps up its intermittent rotation at
all times; but there are times when, because
5 the batteries are fully charged or for other
reasons, the whole installation is cut off from
the main, as will more clearly appear by refer-
ence to my application (Case C) filed July 16,
1888, Serial No. 280,020. Again, it may be that
10 the supply company is not furnishing the quan-
tity of current its contract calls for. In such
cases it is evident that the consumer is either
not getting any energy at all, or is getting less
than he is entitled to, and therefore should not
15 be charged during such periods. If, however,
the revolutions of shaft 17 be recorded during
and only during such time as the full amount
of current is passing through the batteries at
that particular point, it is obvious that proper
20 charge to the consumer can be accurately com-
puted therefrom. This is accomplished by
means of the device shown in Figs. 7 and 17.

The solenoid 56 is included in the same
branch of the main line as batteries when be-
25 ing charged, and consequently is energized
whenever there is a current flowing in that
part of the main. The armature 52 of this
magnet is connected with a spindle, 50, carrying
30 a small worm-wheel, 51, so that when the
maximum current is passing the armature
raises the worm-wheel 51, bringing it into en-
gagement with the worm 57 on shaft 17. Spindle
50 is thereby rotated with shaft 17, and by
35 gears 58 59 actuates the registering device 54.
When, however, there is no current in mag-
net 56, the armature 52, and with it spindle 50,
drops, wheel 57 being caught and held sta-
tionary by stop-pin 55. Then, though shaft
17 continues to rotate, no account will be kept
40 thereof. The same thing will occur if the
charging current falls below that called for by
the terms of the contract. It therefore is to the
interest of the company to keep the current
up to the standard.

45 I have described my said invention in the
form in which a resistance is inserted as by-
path during the period during which the pro-
cess of changing the connections of the sec-
tions of the battery is going on. This will
50 generally be found to be the cheapest arrange-
ment and one that for practical purposes is
sufficient; but it is evident that instead of this
resistance one might use an extra section of
the battery, which would then have to be
55 made with two sections more than were neces-
sary to furnish the pressure required in the
utilization-circuit. There would then at all
times (except during the moments when the
changes of connection were taking place) be
60 a section which was connected neither with
the charging nor discharging circuit, and the
cycle would naturally be varied to suit this
state of things, the simplest mode being first
to place this extraction in parallel with the
65 section about to be charged, then to isolate
the latter, then to place it in parallel with the
section which has just been charged, and then

to isolate the latter, so that it will be ready to
be connected with the battery at the next
change.

I have also described the actuating mech-
anism of the periodic change of connections as
being driven by the charging-circuit or the
local battery. I consider that the latter is de-
cidedly the most advantageous mode of actua-
75 tion; but it is evident that it is not essential
that it should be electrically driven. If the
circumstances are such that there is no objec-
tion to the use of clock-work, the changes of
connection may be made at stated intervals by
80 ordinary mechanism of that kind.

The present application may be regarded as
a division and continuation of my application
filed June 21, 1888, Serial No. 277,712, in which
the apparatus herein described is set forth but
85 not claimed. I do not claim herein the sub-
ject-matter of said prior application; neither
do I claim the particular timing mechanism
described, as that forms the subject-matter of
another application for patent, to wit, Serial
90 No. 280,371, filed July 19, 1888; but

What I do claim herein, and desire to se-
cure by Letters Patent, is—

1. In a system of electrical distribution, the
combination of a closed main charging-circuit,
95 a local working circuit, two or more groups of
secondary batteries, positive and negative ter-
minal contacts for each set of batteries, switch-
levers, one for each group of batteries, con-
tact plates on each lever for connecting with
100 all the battery-terminals, and means for vi-
brating said levers so as to transfer each set
or group of batteries from one circuit to the
other in regular order, substantially as de-
scribed.

2. The combination of a closed charging-
circuit, a working-circuit, two or more groups
of secondary batteries, a branch circuit in-
cluding a resistance approximately equal to
that of each set of batteries, terminal contact-
110 strips for the several sets of batteries, switch
mechanism—such as a series of switch-levers—
for transferring the several sets of batteries from
one circuit to the other, and timing mechanism
controlling said switch mechanism, and also
115 controlling contacts in the circuit of said re-
sistance, whereby the latter is included in the
main when there is no battery therein, sub-
stantially as described.

3. The combination of a closed charging-
circuit, a local working-circuit, two or more
sets of secondary batteries, terminal contact-
strips for each set of batteries, a series of vi-
brating switch-levers carrying each contact-
strips constituting terminals of branch circuits
125 of both the main and local, and other contact-
strips adapted to connect the terminals of dif-
ferent batteries, and mechanism for vibrating
said levers into and out of contact with the
terminals of said batteries, thereby transfer-
130 ring them from one circuit to another, sub-
stantially as described.

4. In a system of electrical distribution, the
combination, with the main circuit, the work-

ing circuit, and two or more groups of batteries adapted to be included in either circuit, of a series of switches for transferring said sets of batteries from one circuit to another, continuously-operating timing mechanism for operating said switches at stated intervals, a resistance, and circuit-connections, also controlled by said timing mechanism for including said resistance in a branch of the main circuit in parallel with each set or group of batteries in the act of transferring the same from one circuit to the other, substantially as described.

5. The combination, with the closed main circuit and charging-circuit, of two or more sets of secondary batteries, a series of contact-strips—two for each set of batteries—a series of switch-levers having strips constituting terminals of branches of both the main and local 15 and other strips for connecting the terminals of different batteries, a rotatory shaft having a series of cams—one for each lever—and means for rotating said shaft at a uniform speed, whereby at regular intervals said levers are 20 connected with and disconnected from said battery contact-strips and the several groups of batteries included for a determined period 25 in the charging-circuit, substantially as described.

6. The combination, with the main circuit, 30 working-circuit, and batteries, of switch mechanism for including the batteries at regular intervals in the working-circuit, a shaft rotating at a uniform rate and controlling said switch mechanism, a registering device, an electro-magnet in the charging-main, and connections between said registering device and said shaft controlled by said magnet, so that the duration of charge of the normal current is registered, substantially as described. 35

7. The combination, with the rotating shaft for operating a circuit-changer and timing mechanism controlling said shaft, registering device, an electro-magnet, and gearing for operating said registering device, connected with 40 the armature of said magnet, so as to be thereby thrown into and out of engagement with said shaft, substantially as described.

In testimony whereof I have signed this specification in the presence of two subscribing witnesses. 45

HENRY EDMUNDS.
